CHARLES L. HEISLER, OF SCHENECTADY, NEW YORK.

ERASING-PENCIL.

1,176,141.

Specification of Letters Patent. Patented Mar. 21, 1916.

Application filed November 21, 1911. Serial No. 661,464.

To all whom it may concern:

Be it known that I, CHARLES L. HEISLER, a citizen of the United States, residing at Schenectady, in the county of Schenectady 5 and State of New York, have invented certain new and useful Improvements in Erasing-Pencils, of which the following is a specification describing the device illustrated by the accompanying drawings.

10 The object is to provide an elongated eraser with a ready means for adjustment; to avoid the necessity of repeatedly replacing a worn rubber remnant; thereby securing convenience and economy in the use of 15 time, patience and rubber; moreover to provide a more compact and shorter length of pencil for a maximum length of eraser and lead, so the device may be placed in a pocket or will not project so far therefrom when it 20 is securely held in a vertical position by a suitable fastener.

Figure 1, shows a part exterior side elevation, and part sectional view with the exterior casing broken away to reveal a section 25 of the eraser, and exposed exterior portion of the lead holder inclosed by the eraser.

Fig. 2, shows a sectional elevation of the case and inclosed eraser with an exterior elevation of the centrally located pencil 30 holder which is of usual construction and has a lead 10, projecting from the lower end thereof. Fig. 3, is an exterior side view of the complete device, illustrating the means for clamping the eraser that projects from 35 the upper end. The dotted portion shows the position of the clamping ring when it is desired to adjust the eraser, insert, or remove it from the case. Fig. 4, is a view taken of Fig. 3, when it is revolved about 40 the axis of the pencil through an angle of 90 degrees. Fig. 5, is a top end view of the eraser shown in Fig. 1. Fig. 6, is a cross-section of the pencil near its middle when fitted with a tubular eraser. Fig. 7, is a 45 cross-section of the pencil when used with two erasers as shown in Fig. 9, and which may be of different material, suitable for either lead or ink erasing. Fig. 8, shows a cross-section when the pencil is used with a 50 single eraser shown in Fig. 10. Fig. 9 shows two erasers which may be made of different material suitable for either lead or ink erasing. Fig. 10 shows a pencil used with a 55 single eraser. Fig. 11 is an end view of the pencil with the eraser crushed.

The device consists essentially of a slotted case 1, having a lead holder 2, of usual construction, arranged within the case, in a manner to conveniently project the lead tip 10, from its lower end 3. The means for 60 clamping and adjusting the lead within the holder 2, are not shown, as they may be any one of the well known constructions. Between the lead holder, and case as shown, is 65 an annular space filled with a movable elongated eraser 4, 4^a, 4^b, or 4^c, which lies alongside the lead in the pencil and projects from the upper end of the case where it is held by a clamp 5 or 5^a, formed thereon by slotting the case as shown at 12 and arranging 70 a ring 6, 6^a, to slide endwise thereon for the purpose of loosening or tightening the clamp when adjusting or fastening the eraser by the crushing action of the clamp. A resilient finger 7, is formed on the ring 6, for the 75 purpose of securing the pencil to a pocket in the usual manner, and for providing a catch 8, for securing the clamp ring 6, in its upper position as shown. The catch 8, engages a hexagonal enlargement or bead 9, 80 formed on the case.

Fig. 1, shows the lead holder 2, extending to the extreme upper end of the clamp 5^a, which in this figure is shown of circular 85 cross section to provide a round eraser, shown also in Fig. 5. In Fig. 2, the lead holder is sufficiently foreshortened to permit the clamp to form a flat ended eraser which is also illustrated in Figs. 3, 4, and 90 11. The pencil holder 2, is arranged with the usual means for adjusting the lead tip 10, as it becomes worn or broken. In the device shown this is done by turning the sleeve 11, which causes a longitudinal movement 95 of the lead 10. The detail or interior construction of the lead holder, and means for moving the lead, are not shown, as they may consist of any one of the several well known devices used for this purpose. Evidently 100 other suitable writing material may be substituted for the "lead" 10, which is to be herein understood to mean any suitable writing material when made into pencil or stick form. Evidently the ordinary forms 105 of eraser can also be used in the clamp 5, when desired. As will be seen from Figs. 2 and 3, the finger 7, is made more resilient and yielding when pressed over a thick hem of a pocket because of the outward elastic pressure of the rubber eraser acting against 110

the clamp 5, and the bead 9, and finally against the catch 8, at the end of the finger 7, the clamp ring 6, being sufficiently loose on the case 1, to permit it to act as a fulcrum. 5 This construction avoids the objection to the lack of resilience in the usual construction of fingers which offer considerable resistance and cause unnecessary effort when pressed over the pocket hem which frequently must be held to aid in doing this.

10 It will be seen from the drawings that the slotted tubular case 1 is contracted at its lower end to tightly embrace the lead holder 2 near its lead projecting end 3. The slot 12 15 extends to near the lower contracted end.

Claims:

1. In a pencil, the combination of a casing, a tubular eraser in said casing and protruding from one end thereof, and means 20 for crushing the outer end of said eraser.

2. In a pencil, the combination of a tubular casing, a movably mounted tubular eraser protruding from the upper end thereof, means for crushing the eraser, a lead 25 protruding from the lower end of the casing, and a holder for supporting said lead, said holder being disposed within the eraser and attached to the lower end of said casing.

30 3. In a pencil, the combination of a tubular casing, erasing means having spaced parts extending along opposite sides of the interior of the casing and protruding from the end of the casing, a lead holder held between said spaced parts of the erasing means within the casing, and means for pressing into contact the opposite faces of said parts of the erasing means beyond the end of the lead holder.

40 4. The combination in a pencil, of a tubular case, a lead-holder mounted within the case, eraser means comprising a soft and a gritty portion disposed within the case and around the lead-holder, a lead protruding 45 from the lower end of the pencil, and means to compress the eraser to cause the soft and the gritty eraser portions to come adjacent to each other when both portions project from the upper end of the pencil.

50 5. In a pencil, the combination of, a case having a bead, an eraser protruding from one end of said case, a member mounted on said case and adapted to assist in retaining the eraser in place, and a garment engaging 55 device movable with said member and having a part which co-operates with said bead to retain said device and member near one

end of the case whereby the eraser is clamped in the case.

6. In a pencil, the combination with a 60 casing, of a lead-holder therein adapted to feed from one end of said casing, an eraser having one end disposed adjacent the lead holder in the casing and the other end protruding from the opposite end of said casing, and means for clamping the eraser in its adjusted position and against said lead holder, said means comprising a ring encircling the casing, a garment clasping device movable with the ring, and interfitting 65 parts on the casing and said device to retain said ring and device in a fixed position, so that said ring will clamp the eraser and lead holder in place.

7. In a pencil, the combination of a casing contracted at one end and a slot extending from the opposite end of said casing to a point near its contracted end, a lead-holder within the casing adapted to feed from said contracted end, an eraser disposed in the 80 casing around the lead-holder and protruding from the slotted end, a member movable along the outside of the casing and co-operating with the slotted end of the latter to clamp the eraser, and a device for retaining said member in a fixed position.

8. The combination with a tubular casing having a slot therein extending from one end lengthwise of the casing, and also having a bead which is located near the outer end of the slotted portion of the casing, an eraser in said casing and protruding from the slotted end thereof, a clamping device on said casing for compressing the outer end of the eraser, and a member secured intermediate its ends to said clamping device, one end of said member constituting a garment clasp and the other end thereof interfitting with said bead to releasably lock the clamping device in clamping position.

9. A pencil comprising a tubular casing having a slot therein, extending from one end lengthwise of the casing, a marking device and an eraser located side by side in the slotted portion of said casing, said eraser protruding from the slotted end of said casing, and a clamping member movable along the casing and adapted to compress the slotted portion thereof to clamp the eraser or marking device in place.
